UNITED STATES PATENT OFFICE.

MAUDE G. BROWN, OF WARREN, PENNSYLVANIA.

HANGER.

1,323,957.

Specification of Letters Patent. Patented Dec. 2, 1919.

Application filed September 12, 1918. Serial No. 253,779.

To all whom it may concern:

Be it known that I, MAUDE G. BROWN, a citizen of the United States, residing at Warren, in the county of Warren and State of Pennsylvania, have invented a new and useful Hanger, of which the following is a specification.

By way of explanation it may be stated that when a rug or other relatively heavy article is suspended on a line for the purpose of beating the rug, the rug tends to sag down and slide inwardly, toward its longitudinal center, because the supporting line curves downwardly, under the weight of the rug. In view of the foregoing, the present invention aims to provide a novel means whereby the rug will be held flat, although suspended from a flexible line, the rug thus being disposed in such a position that it may be beaten thoroughly.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in elevation, a device constructed in accordance with the present invention, assembled with a line; Fig. 2 is a cross section taken approximately on the line 2—2 of Fig. 1, parts being omitted, and portions being shown in section; Fig. 3 is a view similar to Fig. 2 but showing a modification; and Fig. 4 is a view similar to Fig. 2 but showing a further modification.

Referring to Figs. 1 and 2, the numeral 1 denotes a pair of supports, of any desired sort, between which extends a line or other flexible element 2. The numeral 3 denotes a rigid rod, the ends of which are received within rings 4, having widened parts 5 into which are threaded shanks 6 of hooks 7. The hooks 7 receive the line 2 and the shanks 6 bear on the rod 3 to hold the same in the rings 4. The hooks 7 and their shanks 6, therefore, exercise a double func-

tion, in that they constitute a means for holding the rod 3 in the ring 4, and constitute, also, means for suspending the rod 3 from the line 2. Since the rod 3 is rigid, a rug or other heavy object, suspended from the rod, will not sag downwardly, but will hang flat, in a position to be beaten thoroughly.

In Fig. 3, a modified view of the invention is shown. In Fig. 3, the rod is denoted by 8 and is partly surrounded by the numeral 9 which engages the rod 8 yielding but firmly, the ring 9 terminating in a hook 10 adapted to engage the line 2.

In Fig. 4 of the drawings, the rod appears at 11 and is surrounded by a ring 12 into which is threaded a set screw 14, engaging the rod 11, the said screw being supplied at its lower end with a turning head 15. The upper portion of the ring 12 carries a hook 16, adapted to engage the line 2.

Having thus described the invention, what is claimed is:—

A device for suspending rugs during the beating thereof, comprising a rigid rod; rings receiving the ends of the rods; and screws threaded into the rings and engaging the rod at their inner ends, the outer ends of the screws having open hooks located in a common plane with the respective rings, the centers of suspension of the hooks being located directly above the centers of the rings, the internal diameter of the rings being greater than the diameter of the rod whereby the rings may be slipped readily on the ends of the rod, the rod being of circular cross section and the openings in the rings being circular, whereby the rod will so position itself, before the screws are tightened, that the axis of the rod will be disposed directly below the centers of the rings and the points of suspension of the hooks, the difference in the diameter of the rings and the rod causing the rings to stand from the rod through the major portion of the circumference of the rings, thereby affording enlarged bearing shoulders for the edges of the rug.

In testimony that I claim the foregoing as my own, I have hereto affixed my signature in the presence of two witnesses.

MAUDE G. BROWN.
